ABSTRACT

An apparatus (10) for, and method of, placing a plurality of spacers (12) between a parallel opposed anode and cathode (20) of an emissive display includes temporarily securing, by applying a vacuum for example, a first side of one of the anode or cathode to a base (14) having a plurality of electromagnets (16) positioned therein. The electromagnets (16) attract a first side of each of the plurality of spacers (12), thereby positioning each of the spacers (12) in a desired location on a second side of the one of the anode or cathode (20). The spacers (12) may be provided from a shuffling tray (40) having a plurality of openings (42), each opening (42) approximately aligned with one of the electromagnets (16) and shaped so as to present the first side to the electromagnet (16) to the one of the anode or cathode (20).

APPARATUS AND METHOD FOR PLACING SPACERS IN AN EMISSIVE DISPLAY

FIELD OF THE INVENTION

The present invention generally relates to emission displays, and more particularly to a structure for, and method of, affixing spacers in field emission displays.

BACKGROUND OF THE INVENTION

Spacers for field emission displays are known in the art. A field emission display includes an envelope structure having an evacuated interspace region between two display plates. Electrons travel across the interspace region from a cathode plate, upon which electron emitter structures, such as Spindt or carbon nanotubes, are fabricated, to an anode plate which includes deposits of light-emitting materials, or phosphors. Typically the pressure within the interspace region is less than or equal to 10^{-6} Torr.

The cathode plate and anode plate are thin in order to provide low display weight. These thin plates are not structurally sufficient to prevent collapse or bowing upon evacuation of the interspace region. Spacers are structures positioned between the anode and the cathode plate to provide standoff. As a result of the atmospheric pressure, spacers play an essential role in lightweight displays. The spacers, in conjunction with the thin, lightweight plates, support the atmospheric pressure allowing the display area to be increased with little or no increase in plate thickness.

Several schemes have been proposed for providing spacers. Some of these schemes include the affixation of structural members to the inner surface of a display plate, particularly, the anode plate. Such prior art schemes include the heating of the display plate and spacer in order to bond the spacer to the display plate. Such schemes require bonding spacers to the anode plate due to its robustness in heating and oxidizing environments compared to the cathode plate. This method has the disadvantage of spacer misalignment when contacting the cathode resulting in destruction of emitters and shorted column or row conductors. Other disadvantages of prior art schemes include large processing times required to heat display plate and spacers, oxidation of cathode bonding metals associated with high temperatures and glues thereby impacting the quality of the vacuum, and contamination caused by elaborate pick and place equipment required for spacer placement. Furthermore, the spacers may be troublesome to keep in an upright position while installing the second plate, and the pick and place method consumes valuable time, perhaps as much as 30 minutes for a large array.

Accordingly, it is desirable to provide an improved method of affixing spacers in field emission displays. Furthermore, other desirable features and characteristics of the present invention will become apparent from the subsequent detailed description of the invention and the appended claims, taken in conjunction with the accompanying drawings and this background of the invention.

BRIEF SUMMARY OF THE INVENTION

An apparatus for, and method of, placing a plurality of spacers between a parallel opposed anode and cathode of an emissive display. The apparatus temporarily secures, by applying a vacuum for example, a first side of one of the anode or cathode to a base having a plurality of electromagnets positioned therein. The electromagnets attract a first

2

side of each of the plurality of spacers, thereby positioning each of the spacers in a desired location on a second side of the one of the anode or cathode.

5 BRIEF DESCRIPTION OF THE DRAWINGS

The present invention will hereinafter be described in conjunction with the following drawing figures, wherein like numerals denote like elements, and

10 FIG. 1 is an isometric view of a preferred embodiment of the present invention;

FIG. 2 is a cross-sectional view taken along line 1—1 of the preferred embodiment of FIG. 1;

15 FIG. 3 is a cross-sectional taken along line 2—2 of the preferred embodiment of FIG. 1;

FIG. 4 is an isometric view of a spacer placed in accordance with the preferred embodiment of the present invention;

20 FIG. 5 is an isometric view of an electromagnet included in the preferred embodiment of FIG. 1;

FIG. 6 is a top view of a shuffle table used in the preferred embodiment of the present invention; and

25 FIG. 7 is a cross-sectional view taken along line 7—7 of FIG. 6.

DETAILED DESCRIPTION OF THE INVENTION

30 The following detailed description of the invention is merely exemplary in nature and is not intended to limit the invention or the application and uses of the invention. Furthermore, there is no intention to be bound by any theory presented in the preceding background of the invention or the following detailed description of the invention.

35 Referring to FIGS. 1—3, the apparatus 10 in accordance with a preferred embodiment of the invention provides a method for providing separation between a cathode and anode of an emission display by placing spacers 12 in the evacuated interspace region between the anode and cathode. A base 14 is configured for securing a plurality of electromagnets 16. The base 14 may comprise any type of material such as plastic or ceramic, but preferably would comprise a thermoset plastic in order to ensure dimensional stability. While a three by three array of electromagnets 16 is shown for simplicity of description, the number of electromagnets 16 would depend on the number of spacers 12 required, which would depend on the size of the cathode/anode of the emissive display and could number in the hundreds. A plurality of vacuum holes 18 are positioned through the base 14 for attracting and securing the anode 20 temporarily in place around the base 14 while placing the spacers 12.

40 A spacer 12 is shown in FIG. 4 and comprises a rigid portion 22 and a metalized portion 24 on opposed sides. The rigid portion 22 comprises a dielectric material to prevent conduction between the sides, or metalized portions 24, and preferably comprises a ceramic material. The metalized portions 24 comprise any metal that would be attracted to the electromagnet 16, and preferably comprise nickel, iron, or a ferrous alloy. The spacer 12 preferably comprises dimensions of 1 centimeter by 1.8 millimeters by 0.5 millimeters, with the 1.8 millimeters dimension stretching along both the anode and cathode.

45 Referring to FIG. 5, the electromagnet 16 shown in FIGS. 1—3 comprises a column portion 30 having a conductor 32 wrapped therearound. The conductor 32 has first 34 and

50 second 36 ends. The first end 34 is connected to a power source 40 and the second end 36 is connected to a power source 42. The power source 40 is connected to a power source 44 and the power source 42 is connected to a power source 46. The power source 44 is connected to a power source 48 and the power source 46 is connected to a power source 50. The power source 48 is connected to a power source 52 and the power source 50 is connected to a power source 54. The power source 52 is connected to a power source 56 and the power source 54 is connected to a power source 58. The power source 56 is connected to a power source 60 and the power source 58 is connected to a power source 62. The power source 60 is connected to a power source 64 and the power source 62 is connected to a power source 66. The power source 64 is connected to a power source 68 and the power source 66 is connected to a power source 70. The power source 68 is connected to a power source 72 and the power source 70 is connected to a power source 74. The power source 72 is connected to a power source 76 and the power source 74 is connected to a power source 78. The power source 76 is connected to a power source 80 and the power source 78 is connected to a power source 82. The power source 80 is connected to a power source 84 and the power source 82 is connected to a power source 86. The power source 84 is connected to a power source 88 and the power source 86 is connected to a power source 90. The power source 88 is connected to a power source 92 and the power source 90 is connected to a power source 94. The power source 92 is connected to a power source 96 and the power source 94 is connected to a power source 98. The power source 96 is connected to a power source 100 and the power source 98 is connected to a power source 102. The power source 100 is connected to a power source 104 and the power source 102 is connected to a power source 106. The power source 104 is connected to a power source 108 and the power source 106 is connected to a power source 110. The power source 108 is connected to a power source 112 and the power source 110 is connected to a power source 114. The power source 112 is connected to a power source 116 and the power source 114 is connected to a power source 118. The power source 116 is connected to a power source 120 and the power source 118 is connected to a power source 122. The power source 120 is connected to a power source 124 and the power source 122 is connected to a power source 126. The power source 124 is connected to a power source 128 and the power source 126 is connected to a power source 130. The power source 128 is connected to a power source 132 and the power source 130 is connected to a power source 134. The power source 132 is connected to a power source 136 and the power source 134 is connected to a power source 138. The power source 136 is connected to a power source 140 and the power source 138 is connected to a power source 142. The power source 140 is connected to a power source 144 and the power source 142 is connected to a power source 146. The power source 144 is connected to a power source 148 and the power source 146 is connected to a power source 150. The power source 148 is connected to a power source 152 and the power source 150 is connected to a power source 154. The power source 152 is connected to a power source 156 and the power source 154 is connected to a power source 158. The power source 156 is connected to a power source 160 and the power source 158 is connected to a power source 162. The power source 160 is connected to a power source 164 and the power source 162 is connected to a power source 166. The power source 164 is connected to a power source 168 and the power source 166 is connected to a power source 170. The power source 168 is connected to a power source 172 and the power source 170 is connected to a power source 174. The power source 172 is connected to a power source 176 and the power source 174 is connected to a power source 178. The power source 176 is connected to a power source 180 and the power source 178 is connected to a power source 182. The power source 180 is connected to a power source 184 and the power source 182 is connected to a power source 186. The power source 184 is connected to a power source 188 and the power source 186 is connected to a power source 190. The power source 188 is connected to a power source 192 and the power source 190 is connected to a power source 194. The power source 192 is connected to a power source 196 and the power source 194 is connected to a power source 198. The power source 196 is connected to a power source 200 and the power source 198 is connected to a power source 202. The power source 200 is connected to a power source 204 and the power source 202 is connected to a power source 206. The power source 204 is connected to a power source 208 and the power source 206 is connected to a power source 210. The power source 208 is connected to a power source 212 and the power source 210 is connected to a power source 214. The power source 212 is connected to a power source 216 and the power source 214 is connected to a power source 218. The power source 216 is connected to a power source 220 and the power source 218 is connected to a power source 222. The power source 220 is connected to a power source 224 and the power source 222 is connected to a power source 226. The power source 224 is connected to a power source 228 and the power source 226 is connected to a power source 230. The power source 228 is connected to a power source 232 and the power source 230 is connected to a power source 234. The power source 232 is connected to a power source 236 and the power source 234 is connected to a power source 238. The power source 236 is connected to a power source 240 and the power source 238 is connected to a power source 242. The power source 240 is connected to a power source 244 and the power source 242 is connected to a power source 246. The power source 244 is connected to a power source 248 and the power source 246 is connected to a power source 250. The power source 248 is connected to a power source 252 and the power source 250 is connected to a power source 254. The power source 252 is connected to a power source 256 and the power source 254 is connected to a power source 258. The power source 256 is connected to a power source 260 and the power source 258 is connected to a power source 262. The power source 260 is connected to a power source 264 and the power source 262 is connected to a power source 266. The power source 264 is connected to a power source 268 and the power source 266 is connected to a power source 270. The power source 268 is connected to a power source 272 and the power source 270 is connected to a power source 274. The power source 272 is connected to a power source 276 and the power source 274 is connected to a power source 278. The power source 276 is connected to a power source 280 and the power source 278 is connected to a power source 282. The power source 280 is connected to a power source 284 and the power source 282 is connected to a power source 286. The power source 284 is connected to a power source 288 and the power source 286 is connected to a power source 290. The power source 288 is connected to a power source 292 and the power source 290 is connected to a power source 294. The power source 292 is connected to a power source 296 and the power source 294 is connected to a power source 298. The power source 296 is connected to a power source 300 and the power source 298 is connected to a power source 302. The power source 300 is connected to a power source 304 and the power source 302 is connected to a power source 306. The power source 304 is connected to a power source 308 and the power source 306 is connected to a power source 310. The power source 772 is connected to a power source 776 and the power source 774 is connected to a power source 778. The power source 776 is connected to a power source 780 and the power source 778 is connected to a power source 782. The power source 780 is connected to a power source 784 and the power source 782 is connected to a power source 786. The power source 784 is connected to a power source 788 and the power source 786 is connected to a power source 790. The power source 788 is connected to a power source 792 and the power source 790 is connected to a power source 794. The power source 792 is connected to a power source 796 and the power source 794 is connected to a power source 798. The power source 796 is connected to a power source 800 and the power source 798 is connected to a power source 802. The power source 800 is connected to a power source 804 and the power source 802 is connected to a power source 806. The power source 804 is connected to a power source 808 and the power source 806 is connected to a power source 810. The power source 808 is connected to a power source 812 and the power source 810 is connected to a power source 814. The power source 812 is connected to a power source 816 and the power source 814 is connected to a power source 818. The power source 816 is connected to a power source 820 and the power source 818 is connected to a power source 822. The power source 820 is connected to a power source 824 and the power source 822 is connected to a power source 826. The power source 824 is connected to a power source 828 and the power source 826 is connected to a power source 830. The power source 828 is connected to a power source 832 and the power source 830 is connected to a power source 834. The power source 832 is connected to a power source 836 and the power source 834 is connected to a power source 838. The power source 836 is connected to a power source 840 and the power source 838 is connected to a power source 842. The power source 840 is connected to a power source 844 and the power source 842 is connected to a power source 846. The power source 844 is connected to a power source 848 and the power source 846 is connected to a power source 850. The power source 848 is connected to a power source 852 and the power source 850 is connected to a power source 854. The power source 852 is connected to a power source 856 and the power source 854 is connected to a power source 858. The power source 856 is connected to a power source 860 and the power source 858 is connected to a power source 862. The power source 860 is connected to a power source 864 and the power source 862 is connected to a power source 866. The power source 864 is connected to a power source 868 and the power source 866 is connected to a power source 870. The power source 868 is connected to a power source 872 and the power source 870 is connected to a power source 874. The power source 872 is connected to a power source 876 and the power source 874 is connected to a power source 878. The power source 876 is connected to a power source 880 and the power source 878 is connected to a power source 882. The power source 880 is connected to a power source 884 and the power source 882 is connected to a power source 886. The power source 884 is connected to a power source 888 and the power source 886 is connected to a power source 890. The power source 888 is connected to a power source 892 and the power source 890 is connected to a power source 894. The power source 892 is connected to a power source 896 and the power source 894 is connected to a power source 898. The power source 896 is connected to a power source 900 and the power source 898 is connected to a power source 902. The power source 900 is connected to a power source 904 and the power source 902 is connected to a power source 906. The power source 904 is connected to a power source 908 and the power source 906 is connected to a power source 910. The power source 908 is connected to a power source 912 and the power source 910 is connected to a power source 914. The power source 912 is connected to a power source 916 and the power source 914 is connected to a power source 918. The power source 916 is connected to a power source 920 and the power source 918 is connected to a power source 922. The power source 920 is connected to a power source 924 and the power source 922 is connected to a power source 926. The power source 924 is connected to a power source 928 and the power source 926 is connected to a power source 930. The power source 928 is connected to a power source 932 and the power source 930 is connected to a power source 934. The power source 932 is connected to a power source 936 and the power source 934 is connected to a power source 938. The power source 936 is connected to a power source 940 and the power source 938 is connected to a power source 942. The power source 940 is connected to a power source 944 and the power source 942 is connected to a power source 946. The power source 944 is connected to a power source 948 and the power source 946 is connected to a power source 950. The power source 948 is connected to a power source 952 and the power source 950 is connected to a power source 954. The power source 952 is connected to a power source 956 and the power source 954 is connected to a power source 958. The power source 956 is connected to a power source 960 and the power source 958 is connected to a power source 962. The power source 960 is connected to a power source 964 and the power source 962 is connected to a power source 966. The power source 964 is connected to a power source 968 and the power source 966 is connected to a power source 970. The power source 968 is connected to a power source 972 and the power source 970 is connected to a power source 974. The power source 972 is connected to a power source 976 and the power source 974 is connected to a power source 978. The power source 976 is connected to a power source 980 and the power source 978 is connected to a power source 982. The power source 980 is connected to a power source 984 and the power source 982 is connected to a power source 986. The power source 984 is connected to a power source 988 and the power source 986 is connected to a power source 990. The power source 988 is connected to a power source 992 and the power source 990 is connected to a power source 994. The power source 992 is connected to a power source 996 and the power source 994 is connected to a power source 998. The power source 996 is connected to a power source 1000 and the power source 998 is connected to a power source 1002. The power source 1000 is connected to a power source 1004 and the power source 1002 is connected to a power source 1006. The power source 1004 is connected to a power source 1008 and the power source 1006 is connected to a power source 1010. The power source 1008 is connected to a power source 1012 and the power source 1010 is connected to a power source 1014. The power source 1012 is connected to a power source 1016 and the power source 1014 is connected to a power source 1018. The power source 1016 is connected to a power source 1020 and the power source 1018 is connected to a power source 1022. The power source 1020 is connected to a power source 1024 and the power source 1022 is connected to a power source 1026. The power source 1024 is connected to a power source 1028 and the power source 1026 is connected to a power source 1030. The power source 1028 is connected to a power source 1032 and the power source 1030 is connected to a power source 1034. The power source 1032 is connected to a power source 1036 and the power source 1034 is connected to a power source 1038. The power source 1036 is connected to a power source 1040 and the power source 1038 is connected to a power source 1042. The power source 1040 is connected to a power source 1044 and the power source 1042 is connected to a power source 1046. The

second 35 ends that are coupled to a current source (not shown). When current flows through the conductor 32 and in the coil 36 formed around the column portion 30, an electromagnetic field is created in a manner well known to those skilled in the art. A receiving portion 38 integral to the column portion 30 is shaped to receive, while magnetically attracting, one of the metallized portions 24 of the spacer 12. The end 37 of the receiving portion 38 preferably is flush with, or occupies the same plane as, the first surface 13 of the base 14, but may be recessed within the base 14.

The spacers 12 may be individually guided to the electromagnet 16 by the shuffle tray 40 illustrated in FIGS. 6 and 7. A device (not shown) drops a spacer 12 into each of the openings 42 in the shuffle tray 40. As the spacer 12 passes through the opening 42, it is repositioned, if necessary, by the shape of the opening 42 so one of the metallized portions 24 is aligned, as it passes out of the shaped end 44, with the receiving portion 36. The magnetism created by the electromagnet 16 ensures the spacer is accurately positioned in the desired position and in an upright position so the other metallized portion 24 is positioned to receive the other of the anode or cathode. The shuffle tray 40 may be shaken, or vibrated, to facilitate the spacer 12 passing through the opening 42 and out the shaped end 44 in the desired orientation. The shuffle tray 40 may then be moved before positioning the other of the anode or cathode on the spacers 12.

If one or more spacers 12 are positioned incorrectly (misaligned), the apparatus 10 may be subjected to a localized vacuum from above and a selected one or more of the electromagnets 16 may be de-activated. The localized vacuum will then cause the spacer to be pulled from its position. The placing process may then be repeated for that specific location on the anode 20.

The invention described herein provides, in view of known art, improved accuracy in placement in a desired location, reduced contaminants that may degrade the emitters and the vacuum, less consumption of time in placement of the spacers, proper orientation of one or more spacers, and a way of correcting misplacement of the spacers.

While at least one exemplary embodiment has been presented in the foregoing detailed description of the invention, it should be appreciated that a vast number of variations exist. It should also be appreciated that the exemplary embodiment or exemplary embodiments are only examples, and are not intended to limit the scope, applicability, or configuration of the invention in any way. Rather, the foregoing detailed description will provide those skilled in the art with a convenient road map for implementing an exemplary embodiment of the invention, it being understood that various changes may be made in the function and arrangement of elements described in an exemplary embodiment without departing from the scope of the invention as set forth in the appended claims.

The invention claimed is:

1. A method of placing a plurality of spacers between a parallel opposed anode and cathode of an emissive display, comprising:

temporarily securing a first side of one of the anode or cathode to a base having a plurality of electromagnets positioned therein; and

magnetically attracting a first side of each of the plurality of spacers to one of the electromagnets, thereby positioning each of the spacers in a desired location on a second side of the one of the anode or cathode.

2. The method of claim 1 further comprising bonding the first side of the spacer to the one of the anode or cathode.

3. The method of claim 1 further comprising bonding the other of the anode or cathode to a second side of the spacer.

4. The method of claim 1 wherein the temporarily securing comprises attracting the first side of the anode or cathode to the base by a vacuum exerted through a plurality of openings in the base.

5. The method of claim 1 further comprising positioning each of the spacers so the first side thereof may be attracted by one of the electromagnets.

10 6. The method of claim 1 wherein the positioning comprises shuffling the spacers in a tray having a plurality of openings, each approximately aligned with one of the electromagnets and shaped so as to present the first side to the electromagnet.

15 7. An apparatus for placing spacers on one of an anode or cathode of an emissive display, comprising:

a base having a first side for receiving the anode or cathode and having a plurality of openings therethrough for presenting a vacuum existing on a second side to the first side to draw the anode or cathode into contact with the first side; and

a plurality of electromagnets coupled to terminals for receiving a voltage, each positioned within the base to exert a magnetic pull through the anode or cathode to attract and position one of the spacers.

20 8. The apparatus of claim 7 further comprising a shuffle tray having a plurality of openings therethrough, each opening for receiving one of the spacers and positioning the spacer for placement onto the anode or cathode on a side opposed to the base and so as to line up with and be magnetically attracted to one of the plurality of electromagnets.

25 9. The apparatus of claim 7 further wherein the other of the anode or cathode are positioned against a side of the spacer opposed to the side attracted by the electromagnet.

10 10. The apparatus of claim 7 wherein each spacer comprises a rigid center portion of a ceramic material and two opposed sides of metal.

40 11. The apparatus of claim 7 wherein each spacer has a first side comprising a metal that is attracted by the electromagnet.

12. The apparatus of claim 11 wherein the metal comprises one of a nickel, iron, ferrous alloy, or a combination thereof.

45 13. The apparatus of claim 11 wherein the metal bonds the spacer to the one of an anode or a cathode.

14. The apparatus of claim 7 wherein the electromagnet comprises a first column portion having a conductor coiled therearound and a receiving end that magnetically attracts one of the spacers when a current is passed through the conductor.

15. An apparatus for placing spacers on one of an anode or cathode of an emissive display, comprising:

55 a base having first and second sides and a plurality of openings therethrough, the first side receiving the anode or cathode, wherein the anode or cathode is drawn into contact with the first side by a vacuum existing on the second side; and

a plurality of electromagnets coupled to terminals for receiving a voltage, each positioned within the base to exert a magnetic pull through the anode or cathode to attract and position one of the spacers thereon.

60 16. The apparatus of claim 15 further comprising a shuffle tray having a plurality of openings therethrough, each opening for receiving one of the spacers and positioning the spacer for placement onto the anode or cathode on a side

opposed to the base and so as to line up with and be magnetically attracted to one of the plurality of electromagnets.

17. The apparatus of claim 15 further wherein the other of the anode or cathode are positioned against a side of the spacer opposed to the side attracted by the electromagnet.

18. The apparatus of claim 15 wherein each spacer comprises a rigid center portion of a ceramic material and two opposed sides of metal.

19. The apparatus of claim 15 wherein each spacer has a first side comprising a metal that is attracted by the electromagnet.

20. The apparatus of claim 15 wherein the electromagnet comprises a first column portion having a conductor coiled therearound and a receiving end that magnetically attracts one of the spacers when a current is passed through the conductor.
